UNITED STATES PATENT OFFICE.

DENNIS PARKS, OF ST. LOUIS, MISSOURI.

COTTON EXTRACTING AND CLEANING MACHINE.

1,360,015.

Specification of Letters Patent. Patented Nov. 23, 1920.

Application filed March 18, 1918. Serial No. 223,134.

To all whom it may concern:

Be it known that I, DENNIS PARKS, a citizen of the United States, residing in the city of St. Louis and State of Missouri, have 5 invented new and useful Improvements in Cotton Extracting and Cleaning Machines, of which the following is a specification.

This invention relates to certain new and useful improvements in cotton-extracting 10 and cleaning machines of the type heretofore patented to John E. Mitchell and shown, for example, in Patent No. 1,030,913 dated July 2, 1912 and No. 1,129,220 dated February 23, 1915.

15 In each of the machines shown in the above patents it is contemplated that the mixed cotton, hulls and bolls shall be subjected to agitation and impact by means of a revolving member, with the object of breaking up any unopened bolls, or of separating the hulls from bolls which have opened, but from which the cotton has not been extracted. A special form of boll breaker is shown in the latter of the above- 20 named patents, and is more particularly described and claimed in my prior Patent No. 1,081,461 dated December 16, 1913.

25 In operating upon cotton bolls in the manner set forth in the above patents, it has always been found difficult to adjust the degree of breaking action, regulated by the speed of rotation of the breaking cylinder, to the character of the bolls being treated, which in different seasons, or in different 30 periods of the same season, and even in the same mass of raw material, will frequently vary considerably in the degree of toughness or brittleness. This difficulty may be stated, briefly, to reside in the fact that if 35 the breaker is rotated at a speed adapted to break up bolls that are relatively tough, such, for example, as damp bolls, bolls that are dry and relatively brittle will have their hulls practically pulverized, rendering it extremely difficult to separate the fine hull particles from the cotton.

40 The above difficulty was long since recognized, and in Patent No. 1,120,220, means outside of the breaking chamber are provided for acting on bolls which may not have been reduced, by the initial breaking action. It has since been discovered, 45 however, and demonstrated by commercial machines, that the best results are secured by acting on all of the bolls in the breaking chamber.

It is the general object of the present invention therefore, to accomplish the breaking up of cotton bolls, of whatever character, and no matter how much they may vary 60 in toughness, or brittleness, in the same mass, in a continuous operation in a single breaking chamber, without the attendant disadvantage of crushing, or pulverizing the hulls, above alluded to.

65 With this object in view, I provide a machine which will normally have a uniform degree of breaking action upon the bolls, and which will provide automatically for the removal of the cotton and hulls of 70 broken bolls as soon as disintegration occurs, and for continued action upon bolls tougher than those of an average character, whereby I avoid subjecting the hulls of broken bolls to the repeated action of the breaker 75 which, as stated, tends to pulverize the hull sections broken off from the bolls. According to this invention, therefore, should the same batch of raw material contain bolls varying in their degree of toughness or 80 brittleness, all the bolls will be uniformly broken up, as the more brittle bolls will be rapidly disintegrated and the cotton and hulls thereof instantly drawn out of the 85 breaking chamber, while the tougher bolls will be prevented from passing out of the chamber until they in turn have been broken up by the repeated impact action of the breaking cylinder.

90 The invention likewise involves means for adjusting the degree of treatment in the breaking chamber without varying the intensity of the breaking action, to provide for variations from average conditions; as, for example, where the bolls are of sub- 95 stantially uniform character, but are either uniformly smaller, or tougher, or more brittle, than the average. Such adjustment of the degree of breaking action is effected, in the present embodiment of the invention, by 100 regulating the discharge from the breaking chamber, so that the bolls may be retained in the latter a longer or shorter time according to their degree of toughness; or, if they are uniformly small, be prevented from escaping 105 from the breaking chamber until their hulls have been completely broken off.

My invention is illustrated in the accompanying drawings in which,—

110 Figure 1 is a view in end elevation of a machine constructed according to my invention; and,

Fig. 2 is a central, vertical section, looking from the opposite end of the machine to that shown in Fig. 1.

Referring now to the drawings, the numeral 1 indicates the casing of the machine, which is provided with a hopper 2 in which are mounted a pair of feed rollers 3 on shafts 4, revolving toward each other, as indicated by the arrows. Each of these rollers is provided around its circumference, as usual, with gripping surfaces to engage the cotton and force it down into the machine. The numeral 5 indicates a boll-breaking cylinder, which is mounted on a shaft 6 and revolves in the direction indicated by the arrow. The breaking cylinder 5 is partially surrounded by a casing, comprising a screen 7 and a casing member 8, the screen permitting an initial separation of dirt and refuse from the cotton, as will be understood. Mounted on the breaking cylinder are a series of beater-arms 9, which rotate in proximity to said screen and casing member and operate to break the bolls by impact therewith, so as to separate the hulls forming the bolls, as distinguished from a crushing action, such as would be produced by mashing or grinding the bolls. In fact, the casing merely acts, in this regard, to direct the course of the cotton and bolls in the breaking chamber, and to hold them in sufficiently close proximity to the breaking cylinder to permit the beater-arms to strike the bolls. The numeral 10 indicates an outlet from the breaking chamber across which, and partly closing it, extends an angle-bar 11 which is secured to the underside of a rod 12, the latter extending from end to end of the machine, and being mounted in suitable bearings in the end walls of the latter. At one end the rod 12 extends through the end wall of the casing and has secured on such extension, by a set-screw 13, the upper end of a lever 14, to the lower end of which is pivotally connected one end of a bar 15, the other end of which extends through a keeper 16 at the front of the machine, and is provided on its lower side at said end portion with a series of notches 17, one or the other of which may be brought into engagement with the keeper 16. By disengaging the bar 15 from the keeper 16 and pulling it outward, or pushing it inward, the rod 12 may be turned to vary the position of the angle bar 11 relative to the bottom edge of the opening 10, as well as its distance from a picker roll 18, whereby to increase or decrease the capacity of the discharge outlet from the crushing chamber. The picker roll 18 comprises a cylinder provided around its circumference with a series of longitudinally-extending channel-bars 19, and is mounted on a shaft 20 to be rotated in the direction shown by the arrow. At its upper side the picker roll 18 is sur-

rounded by a concaved frame member 21, which is shown to be lined on its inner side with sheet metal 22, and to the rear end of the frame piece 21 is connected the upper end of a curved sheet-metal member 23, which is connected at its ends to the end walls of the machine, and constitutes a portion of the casing proper. At its lower side the picker roll 18 is surrounded by a curved guard 24, located in sufficiently close proximity thereto to prevent cotton, or pieces of hull, from falling between said picker roll and the guard. The upper inner end of the guard 24 is shown to be connected to the upper outer end of the casing member 8, the edge of which latter forms the lower edge of the discharge opening 10. It will be understood, of course, that both the guard 24 and the casing 8 extend transversely of the machine from end to end thereof. The guard 24 is mounted on cross-bars 25 and 26, which latter also supports the upper end of the casing member 8. The curved sheet-metal frame member 23 extends a considerable distance below the picker roll 18, and with the cross-bar 25 confines an uninterrupted space, indicated by the numeral 27, providing an agitating chamber. The numeral 28 indicates the saw cylinder, mounted on a shaft 29; the numeral 30, a kicker roll, mounted on a shaft 31; and the numeral 32, a doffer roll, mounted on a shaft 33, these members being adapted to rotate in the directions shown by the arrows thereon, and operating in the same manner as shown and described in the patents above referred to. That is to say, the cotton is carried around by the saw cylinder and continuously removed therefrom by the doffer roll; while the hull particles are knocked back by the kicker roll, and eventually pass out of the machine. In place of the double hull board shown in the Mitchell Patent No. 1,030,913, I prefer to use a single adjustable hull board 34 below which is mounted, on a shaft 35, a smooth roller 36, rotating in the direction shown by the arrow, and replacing the lower hull board of the said Mitchell patent. These features, however, form no part of the present invention and will be described and claimed in a separate application to be filed by the said John E. Mitchell.

The numeral 37 indicates a conveyer mounted on a shaft 38, for removing refuse from the machine. A space 39 is provided between the screen 7 and the casing of the machine, which terminates in a chamber 40 in which is a conveyer 41 on a shaft 42 for removing dust, or other particles passing through the screen 7. Extensions of various shafts entering into the driving mechanism are shown in Fig. 1, which shafts are provided with pulleys over which travels a belt 43 causing the said shafts to be rotated in the directions shown by the arrows in Fig. 130

2. The driving pulley 43^a is on the opposite side of the machine from that shown in Fig. 1, and is fast on the shaft 33, on the same end of which is a pinion 44 meshing with 5 a gear 45 which rotates the shaft 39 of the saw cylinder. On the opposite end of the shaft 33 is mounted a pulley 46 which causes the travel of the belt 43. The smooth roll 36 is rotated from the shaft 38 by means of 10 a pinion 47 on said shaft in mesh with a gear 48, on the shaft 35 of said smooth roller. A belt tightening pulley 49 is supported on a lever arm 50 which is pivotally mounted on the rod 12 and which may be 15 held in adjusted positions through the medium of a slotted extension 51, the slot of which works over a stud 52 which is provided with a lock-nut 53. A window 54 is preferably provided at one end of the machine 20 through which the action taking place in the agitating chamber may be seen.

The shaft 31 is mounted in adjustable hangers 55 so that the distance of the picker roll 30 from the saw cylinder may be adjusted as circumstances may require.

In the operation of the machine, the cotton as picked, including cotton bolls, is fed into the machine by means of the feed rolls 4 from the hopper 2, or cotton bolls only may 30 be so fed. As soon as the bolls, either open or closed, enter the breaking chamber, they are subjected to the impact of the revolving beater arms 9 and when broken up, the cotton and adhering hulls are drawn through 35 the discharge opening 10 by the picker roll 18 and delivered to the agitating chamber 27, where the cotton is separated from the hulls by the action of the saw cylinder and kicker roll in the usual manner. Any un- 40 broken bolls will fall down in the breaking chamber and be again subjected to impact from the beater arms 9. This continues until they are broken apart when the picker roll will in turn draw the cotton and ad- 45 hering hulls through the opening 10. The speed of rotation of the crushing cylinder is relatively moderate, so that the brittle bolls may be rapidly broken up by a series of light blows and their hull particles be 50 instantly carried out of the breaking chamber by the picker roll before the hulls have been crushed, or broken up into small pieces, by the action of the beater arms. The 55 tougher bolls will simply remain in the breaking chamber, and be subjected to repeated impact action of the breaking cylinder until they are broken apart, as an un- 60 broken boll cannot pass out of the discharge opening 10. It will readily be seen that by this arrangement I provide against repeated action of the breaking cylinder on the brittle hull particles, which would tend to pulverize them, and also that I obviate the necessity of rotating the breaking cylinder

at such a speed as to break the tougher bolls 65 at the same time that the brittle bolls are broken, which increase in the intensity of action of the breaking cylinder would also tend to pulverize the hulls of the brittle bolls. In other words, my invention pro- 70 vides for the gradual or progressive disintegration of the bolls according to the degree of their brittleness, the hull particles and cotton of each character of boll being promptly drawn from the machine as soon 75 as the boll is broken up or disintegrated, thus, as stated, preventing unnecessary breaking up and pulverizing of hull particles which have already been broken away from the boll.

I desire to emphasize the importance of the particular manner of breaking up, or disintegrating, the bolls above described. It is vitally essential to the successful operation of the machine that the bolls be broken without breaking or crushing the hull sections separated from the bolls in the breaking action. It is necessary that such hull sections remain intact so that they can be separated from the cotton by the kicker roll 80 rotating above the saw cylinder. If the hulls have been broken up, or crushed, the small particles will be carried through by the saws with the cotton; whereas, if they have not been damaged, or broken, the kicker roll knocks them out of the cotton. To avoid crushing the hulls, I rely solely upon impact action, caused by relatively light blows 85 of arms on a rotating member. Such action 90 simply breaks the bolls apart at the point where the hulls joint on the stems, without crushing the hulls and puts the mass in the 95 most desirable shape for separating the cotton from the hulls.

It should also be remarked that the provision of means for insuring the prompt withdrawal of the hulls and cotton from the breaking chamber is quite as important as the manner of breaking the bolls referred to. It will be noted that one side of the discharge opening from the breaking chamber is in motion through the rotation of the picker roll, thereby insuring a free discharge for all loose cotton and hulls, which are withdrawn immediately from the breaking chamber. This permits running the breaking cylinder at a moderate speed, so that hulls of the most brittle bolls are readily separated from each other, without being damaged or crushed, and instantly discharged from the breaking chamber; while the tough bolls, and bolls of medium toughness, remain longer within the breaking chamber and are struck as many blows by the beater arms as are necessary to break the hulls apart at the stem, the number of 120 blows required in each case depending upon the toughness of the boll. But in all cases,

as soon as the hulls are broken apart, they are instantly drawn through the discharge opening with the cotton by the picker roll, and are not themselves broken up or 5 crushed.

Machines embodying the above principle of operation are now in commercial operation and the results obtained represent a great advance in the art of cleaning cotton, 10 as these machines not only permit a more complete separation of the hulls from the cotton, but the cotton extracted from the closed bolls is discharged from the machine in a clean condition, and is thoroughly 15 drawn out, or loosened up, by the action of the picker roll, and subsequently by that of the saw cylinder. These machines have not only shown, in operation, that a large amount of boll cotton which would otherwise be wasted can be extracted, but that 20 said cotton is rendered more salable than would otherwise be the case, by being placed in a condition, as to cleanliness and character, substantially on a par with hand-picked 25 cotton.

I claim:—

1. A cotton extracting and cleaning machine, comprising, in combination, a boll breaking chamber having an outlet, means 30 located in said chamber for breaking bolls, an agitating chamber having working communication with said boll breaking chamber, cotton separating mechanism operating in the agitating chamber, and means for regulating the progressive discharge from 35 the outlet of the boll breaking chamber into the agitating chamber of the disintegrated bolls in the order of their reduction.

2. A cotton extracting and cleaning machine according to claim 1 in which the 40 means for breaking the bolls are rotatably mounted in the boll breaking chamber.

3. A cotton extracting and cleaning machine according to claim 1 in which the boll 45 breaking means operates by impact on the bolls.

4. A cotton extracting and cleaning machine comprising in combination, a boll breaking chamber having an outlet embodying 50 a stationary and a rotatable member, and of a size to permit broken bolls only to pass therethrough, means located in said chamber for breaking bolls, an agitating chamber having working communication with 55 said boll breaking chamber, and cotton separating mechanism operating in the agitating chamber, said rotary member being adapted to withdraw from the boll breaking chamber and discharge into said agitating chamber, the cotton and hulls of disintegrated bolls in the order of the reduction 60 of the latter.

5. A cotton extracting and cleaning machine, comprising in combination, a boll 65 breaking chamber having an outlet, a

breaker for bolls mounted in said chamber and operating to break the bolls by impact only, an agitating chamber having working communication with said boll breaking chamber, cotton separating mechanism operating in the agitating chamber, and a picker roll for withdrawing from the boll breaking chamber and discharging into the agitating chamber, the cotton and hulls of the disintegrated bolls in the order of the 70 reduction of the latter.

6. In a cotton extracting and cleaning machine, in combination with a chamber, a boll breaker mounted therein and adjusted to break the more brittle bolls only of a 80 given mass of raw material in a given time, cotton separating mechanism remote from said chamber, means for withdrawing from the chamber and delivering to said cotton separating mechanism the cotton and hulls 85 of disintegrated bolls in the order of their reduction, and means for preventing the escape from said chamber of the tougher bolls until they have been broken by repeated action of the boll breaking means. 90

7. In a cotton extracting and cleaning machine, in combination with a chamber, a rotary impact boll breaker mounted therein, and operating to break the more brittle bolls only of a given mass of raw material in a 95 given time, cotton separating mechanism remote from said chamber, means for withdrawing from the chamber and delivering to said cotton separating mechanism the cotton and hulls of disintegrated bolls as reduced, and means for preventing the escape from said chamber of the tougher bolls until 100 they have been broken by repeated action of the boll breaker.

8. In a cotton extracting and cleaning 105 machine, in combination with a chamber provided with means for breaking bolls and having a discharge outlet of a size to pass broken bolls only, cotton separating means, and a picker roll forming one side of, and 110 rotatably mounted adjacent to said discharge outlet and between the latter and said cotton separating means.

9. In a cotton extracting and cleaning machine, in combination with a chamber 115 provided with means for breaking bolls and having a discharge outlet, means for varying the size of said outlet, cotton separating means, and a picker roll rotatably mounted outside of said chamber adjacent to said 120 discharge outlet and between the latter and said cotton separating means.

10. In a cotton extracting and cleaning machine, in combination with a chamber provided with means for breaking bolls and 125 having a discharge outlet, cotton separating means, a picker roll rotatably mounted adjacent to said discharge outlet and between the latter and said cotton separating means, and an adjustable member movable toward 130

and from said picker roll and adapted thereby to vary the size of said discharge opening.

11. In a cotton extracting and cleaning machine, in combination with a chamber provided with a rotary-impact boll breaker, and having a discharge outlet of a size to prevent unbroken bolls from passing therethrough, cotton separating means, and a

picker roll forming one side of, and located adjacent to said discharge outlet for drawing the cotton and hulls of broken bolls through said discharge opening and delivering the same to the cotton separating means.

In testimony whereof I have hereunto set my hand.

DENNIS PARKS.
